UNITED STATES PATENT OFFICE.

ANNA E. MOYER, OF SCHWENKVILLE, PENNSYLVANIA.

DRESSMAKING APPLIANCE.

1,262,376.

Specification of Letters Patent.

Patented Apr. 9, 1918.

Application filed October 31, 1916. Serial No. 128,761.

To all whom it may concern:

Be it known that I, ANNA E. MOYER, a citizen of the United States, residing at Schwenkville, in the county of Montgomery and State of Pennsylvania, have invented 5 certain new and useful Improvements in Dressmaking Appliances, of which the following is a specification.

This invention relates to dressmaking appliances and more particularly to means for fitting waists and for taking measurements for making dresses, and for similar purposes.

One of the main objects of the invention is to provide an appliance which may be fitted to a person for whom it is desired to make a waist or dress so as to take the required measurements, and is also adapted to have the material secured directly to the appliance so as to be marked for cutting out 20 the lining or foundation of the waist. A further object is to provide a device of the character stated composed of a plurality of detachably connected members which may be quickly and easily secured about the person, 25 and as easily removed. Further objects will appear from the detailed description.

In the drawings:

Figure 1 is a front view of the device as applied for taking measurements for a waist;

Fig. 2 is a side view;

Fig. 3 is a view of the device as used for taking measurements for a skirt;

Fig. 4 is a fragmentary detailed view of one of the tapes of which the device is composed;

Fig. 5 is an underneath view of one of the tapes;

Fig. 6 is a section on line 6—6 of Fig. 7;

Fig. 7 is a fragmentary detailed view of 40 the connections between two of the tapes which cross.

In using my device suitable tapes are placed about the neck, waist, and other portions of the body, where it is desired to take 45 measurements, these tapes being indicated by the numerals 1, 2, 3, and 4. Each of these tapes is provided with a plurality of spaced heads 5 on its outer face and, on its under face, near one end, with a socket 6, 50 the heads and socket being adapted to cooperate to form the well known snap connection. The heads 5 are equally spaced, being placed a suitable distance apart, as one half inch, and the tapes are graduated, 55 the graduation marks being numbered in order, as in Fig. 4 of the drawings. By

passing the tapes about the person's body and securing the socket 6 over one of the heads 5, and noting the number at which the socket 6 is placed the person's measurement at this point is taken simultaneously with the securing of the tape in position. A back tape 7 is secured at the center of the neck tape 1 and to the succeeding tapes 2, 3, and 4, this tape extending down the center 60 of the person's back. This tape 7 is provided on its under face with a plurality of suitably spaced sockets similar to the sockets 6 which receive the heads 5 of the horizontal tape. A similar tape 8 at the front 70 is secured in the same way to the tapes 1, 2, 3, and 4. A shoulder tape 9 is secured to each side of the neck tape 1 at one end and at the other end to the heads 10 of the arm tape 11 which is passed about the arm in 75 the usual manner. This arm tape is also provided with a socket corresponding to the socket 6 which cooperates with the heads 10 to secure the tape in position and also indicate the measurement for the arm. 80

At each side a side tape 11^a is detachably secured at its upper end to the bottom or underneath of the arm tape 11 and to the horizontal tapes 2, 3, and 4, this tape 11^a being provided on its inner face with a plurality of suitably spaced sockets corresponding to the socket 6 and coöperating with the heads 5 and 10 of the arm tape and the horizontal tape so as to detachably secure the side tape in position. 90

The outer surfaces of the front, back, side, and shoulder tapes are also graduated in the same manner as the horizontal tapes which are passed about the body of the person being measured. 95

With the various tapes secured in position in this manner, the material for the lining may be pinned to the tapes and the lines on which it is desired to cut this material traced thereon in pencil, the tapes being used as 100 guide lines. This material may then be removed and cut in the usual manner to give the various parts of the lining for the waist, allowance being made in cutting for seams, and these parts then being sewed together. 105 By noting the numbers at which the various sockets for securing the ends of the tapes together are positioned, the desired measurements for the waist may be ascertained before removing the appliance. After the lining has been marked and the measurements noted, this appliance may be quickly and 110

easily removed by simply disconnecting the securing sockets from their coöperating heads.

When it is desired to take measurements for the skirt the same system may be used, the horizontal tapes 12 and 13 being placed where it is desired to take measurements, and the vertical tapes 14, 15, and 16 being secured to these horizontal tapes by means 10 of sockets carried thereby corresponding to the socket 6, and the suitably spaced heads 17 and 18 carried by the tapes 12 and 13. This same system may also be used in taking measurements for the sleeves of the waist or 15 similar purposes.

When not in use, this device may be quickly and easily disassembled and packed in a small container or package for transportation, the tapes being made of any suitable fabric and flexible so as to be easily folded and packed.

I am aware that there have been various systems proposed for taking measurements and charting patterns for dressmaking purposes but, so far as I know, none of these systems has ever employed a device or appliance similar to mine composed of a plurality of detachably connected flexible tapes provided with means for securing the tapes together and for simultaneously taking the desired measurements of the subject to which it is desired to fit a garment.

There may be slight changes made in the construction and arrangement of the different parts of my invention without departing from the field and scope of the same, and I intend to include all such variations, as fall within the scope of the appended claims, in this application in which a preferred form 40 only of my invention is disclosed.

What I claim is:

1. In a device of the character described, a plurality of tapes each provided with a

longitudinal series of outwardly directed securing heads extending longitudinally the 45 full length thereof and an inwardly directed securing socket at one end coöperating with said heads for securing said tape about a person's body, and a plurality of tapes disposed transverse to the first said tapes and 50 each provided with a longitudinal series of inwardly directed spaced securing sockets adapted to coöperate with the heads of the first mentioned tapes for detachably securing all of said tapes together. 55

2. In a device of the character described, the combination of a plurality of spaced horizontally disposed tapes each provided with a longitudinal series of equally spaced securing heads and a securing socket coöperating with said heads for detachably securing the overlapping ends of the tape together, and a plurality of vertically disposed tapes detachably secured to the said horizontal tapes. 65

3. In a device of the character described, the combination of a plurality of horizontally disposed tapes each provided on its outer face with a plurality of equally spaced heads and, on its inner face, with a socket 70 coöperating with said heads for detachably securing the overlapping ends of the tape together, a front tape detachably secured to the horizontal tapes, arm tapes similar to the said horizontal tapes, shoulder tapes detachably secured to the uppermost of the said horizontal tapes and to the arm tapes, and side tapes detachably secured to the arm tapes and the said horizontal tapes. 75

In testimony whereof I affix my signature 80 in presence of two witnesses.

ANNA E. MOYER.
